UNITED STATES PATENT OFFICE.

FRITZ W. A. HENRICI, OF BOSTON, MASSACHUSETTS.

REVERSING MECHANISM.

1,316,093.

Specification of Letters Patent. Patented Sept. 16, 1919.

Application filed April 12, 1916. Serial No. 90,762.

To all whom it may concern:

Be it known that I, FRITZ W. A. HENRICI, a citizen of the United States, and a resident of Boston, county of Suffolk, and Commonwealth of Massachusetts, have invented an Improvement in Reversing Mechanism, of which the following description, in connection with the accompanying drawings, is a specification, like characters on the drawings 10 representing like parts.

This invention relates to driving and reversing mechanism adapted for use in any case where it is desired to effect periodical reverse motion of a machine, and aims to 15 produce a novel, effective and inexpensive construction for that purpose, to be operated by the driven member.

My invention will be more easily understood by reference to an illustrative embodiment thereof, and in which—

Figure 1 is a vertical cross-section on the line 1—1, Fig. 2, looking toward the right;

Fig. 2, a vertical longitudinal section on the line 2—2, Fig. 1, looking toward the left;

Fig. 3, a diagrammatic illustration of the disposition of the circuit-breaking members and wires leading thereto and therefrom, showing the directions of flow of electric currents when the members are in certain 30 positions;

Fig. 4, a similar illustration of the same parts when the circuit-breaking members are in different positions, and

Fig. 5, a detailed plan of some of the 35 contacts.

Referring first to Figs. 1 and 2, my invention is shown as comprising a supporting and inclosing case A, of suitable material, as metal, and herein pear-shaped in vertical 40 cross section, having front and rear end walls 1, 1. The case is provided with a bearing 2 on its rear wall. The opposite and front wall 1, of the case has an opening or handhole therein covered by a plate 3, which 45 may be secured to the case A, by suitable means as screws 4, 4, and this plate 3 has a bearing 5, opposite to the bearing 2 referred to. The top, bottom and side walls of the case A may consist of a metal plate 50 6 carried about and resting on the flanges 7, 7, of the walls 1, 1, and having its opposite ends suitably secured.

A rib 8 of suitable dimensions extends from the front to the rear wall of the case, 55 and furnishes convenient means of support for certain other members to be referred to.

Extending longitudinally through the case A, Fig. 2, is a threaded timer and circuit-breaker carrying shaft 9 carrying a shaft-supporting and timer-reversing member 10, as a sleeve, near one and herein the rear end thereof, and which is locked suitably thereon. A collar 11 is secured conveniently upon the sleeve 10 abutting the bearing 2 of the case A, and thus acts to 60 prevent longitudinal movement of the shaft 9 toward the right. The sleeve 10 is enlarged diametrically near one end producing a shoulder 12.

Adjacent its opposite end, Fig. 2, the shaft 70 9 carries threaded thereto a second shaft-supporting and timer-reversing sleeve 13, the position of the sleeve longitudinally on the shaft 9 being determined and adjusted by a collar 14 on the outer end of the shaft. 75 The outer end of the sleeve 13 is provided with a plurality of notches or slits 14^a, to receive teeth 14^b formed on the inner reduced edge of the collar 14, the reduced edge serving as a support for the outer end 80 of the sleeve 13.

This collar 14 is retained on the shaft 9 by screws 14^c, 14^c, one of which enters a keyway 14^d, while the other engages a flat face 14^e of the shaft. This sleeve 13 has an adjusting hand wheel 15, secured thereto. By means of the foregoing members obviously the sleeve 13 may be longitudinally adjusted on the shaft 9 for a purpose which will be explained presently. The sleeves 10, 13, are 90 each provided at their opposing faces with longitudinally extended timer-throwing posts 10^a, 13^a.

Threaded to the shaft 9 between the sleeves 10—13, Fig. 2, is a traveling combined timer and circuit-breaker actuating member, as a nut 16, having at substantially opposite points on its two faces, longitudinally extended reversing member engaging posts 16^a, 16^b, adapted to engage the posts 10^a, 13^a, on the timer reversing sleeves 10, 13. 95

Rotatably mounted upon the sleeves 10, 13, Fig. 2, is a circuit-breaker or cam carriage B, which acts also as a current distributing member. This carriage comprises an end disk 17, a similar opposite end disk 18 having an extended sleeve 19 thereon, the sleeve provided at its outer end with a hand-adjusting wheel 20.

These two disks 17, 18, Fig. 2, are securely 110 locked together by suitable tie members, as bolts 21, 21, 21. The disk 17 is positioned

on the sleeve 10 between the shoulder 12 and adjacent the bearing 2 and thus acts to prevent any longitudinal movement of the shaft 9 toward the left Fig. 2. Extended also between these disks, Figs. 1, 2, are timer engaging pins 22, 22, for engaging the timer 16 and for actuating the cam carriage B, the timer nut 16 being grooved at 23, 23, to receive them; and the pins are 10 preferably inclosed by a tubular member as a sheet of metal 21^a, to prevent oil from reaching the parts to be presently described.

This reversing mechanism is particularly adapted for use in connection with a 15 motor as the driving medium, and for controlling the operation of the motor by the construction described, I have conceived novel and effective means, which I will now describe.

20 For closing and opening the several electric circuits to the reversing motor to be referred to and from the generator or other source of power, I prefer to use cams and they are herein three in number; two of them controlling the circuits to the motor, I have called operating cams or circuit breakers 24, 25; and a third one controlling the reversing switch circuit, I have termed a switch cam 26 or circuit breaker, the latter being somewhat shorter than the others and all are carried by pins 21, 21, 21, best shown in Fig. 2.

In this figure the cams are shown for the purpose of clearness, as if they were rotated 35 a partial turn to the right, Fig. 1, with the posts 16^a, 16^b, in horizontal position. Within each cam and about each of the pins 21, 21, 21, is a suitable insulating member 27, and within the cams and carried thereby is a 40 tubular insulating member 28. To guard against too great movement of the cam carriage B, I provide it with a frictional holding device comprising a plate 29 resiliently supported upon two springs 29^a positioned 45 by posts 29^b, supported by any convenient part of the case A. At substantially the center of the plate 29 is a hump or rib 29^c.

When the carriage B is moved, the post 50 25^a, extended laterally from the disk 18, contacts with plate 29 which yields sufficiently to permit the post 25^a to pass under the action of the timer 16 but prevents it from rotating freely, if for any reason, it is inclined to do so. To prevent the carriage B from stopping midway between the contacts 55 32^a and 31^b and adjacent contacts on each side of the cams and thus stopping the machine, if through any accident it was inclined to do so, I have provided the sharply 60 inclined hump 29^c, which compels the post 25^a to stop on one side of the hump and not directly on it. To properly insulate these cams 24, 25, 26, from each other, I have provided between them a plurality of disk-like insulators 30.

For carrying the contacts of the several electric circuits, Fig. 2, to be engaged by the cams 24, 25, 26, I utilize the rib 8, previously referred to. Upon this rib are mounted contact plates 31, 32, by means of 70 binding posts 33^a, 33^b, said posts having connected thereto the lines 34, 35, from the generator, not shown. It is to be understood that hereafter whenever the word "generator" is used, that it is used generally 75 as referring to any source of electric current, as clearly it is immaterial what the source of the current may be.

There is also, Fig. 2, a third contact plate 33 carried by the rib 8, secured by the binding post 36 and having connected to it the line 37 leading Fig. 3, to a reversing switch C. Each contact is properly insulated as by members 38, 38. This switch C may be of any approved type, and is conventionally 80 illustrated Fig. 3, as comprising a magnet 37^a connected with the lines 37, 35, contacts 37^b, 37^c, interposed in the line 35, the magnet 37^a adapted to be energized to throw the armature 37^d against the contacts 37^b, 90 37^c, and thus complete the circuit through the operating circuit breaking cams 24, 25.

At one side of the case A, and near the lower part thereof, Fig. 1, is an upwardly extended rib 39 and there are secured to it 95 what, for convenience, I term constant contact members 40, 41, 42, by binding posts 43, 44, 45, which also secure to said contacts, wires 46, 47, leading to the armature of the reversing motor 47^a, Figs. 3, 4, and a wire 100 48 to the generator line 34.

The outer ends of these contacts 40, 41, 42, see Fig. 1, are bent in such a way as to form resilient cam engaging ends to be engaged by the cams 24, 25, 26, when either of the 105 cams are in position to do so.

The contact plates 31, 32, 33, are forked, see Fig. 5, having each two depending cam-engaging contact arms 31^a, 31^b, 32^a, 32^b, 33^a, 33^b, the arms 31^a, 32^a, depending at the left-hand side, Fig. 1, of the cams 24, 25, 26, while the other and opposite arms 31^b, 32^b, 33^b, depend at the opposite or right-hand side of the cams, opposite and in suitable position to be engaged by the cams. These 110 depending, oppositely disposed contacts I have termed, for convenience, alternating contacts.

The arms 31^a, 31^b and 32^a, 32^b, however, do not depend opposite each other, respectively, but are crossed, see Figs. 4 and 5, in order that the current may be conducted to the motor in either direction.

For operating the shaft 9, Fig. 2, and the several parts already described from 125 the driven member, the shaft 9 may be equipped with any convenient means, and herein is provided with a dog 49, adapted to be engaged by a suitable member, as a dog 50 on the shaft 51 of the driven member. 130

The operation of my improved mechanism is as follows:

From what has been said already, it will be apparent that at all times, the cams 24, 25, 26, are in engagement with the contacts 40, 41, 42, and either contacts 32^b, 31^b, 33^b, or 31^a, 32^a, 33^a, respectively. Assuming then, the several parts to be in position shown in Fig. 1, and referring to Fig. 3 for a grammatical disposition of these parts, and of the connections, the machine to be driven will be assumed to be operatively connected to the motor 47^a, and rotated in such direction as will cause its shaft 51 and dog 50 to rotate shaft 9 of the reversing mechanism in the direction of arrow, Fig. 2, *i. e.*, from left to right. Under these conditions, the current will flow from the generator over line 34 to contact plate 31, contact 31^b, cam 25, contact 41, line 47, armature of motor 47^a, line 46, contact 40, cam 24, contact 32^b, plate 32, line 35, through the switch 37^d, back to its source.

As the nut 16, threaded to shaft 9 cannot rotate, being restrained by the pins 22, 22, it will, by the rotation of shaft 9, be caused to travel longitudinally thereon from right to left, Fig. 2. As the machine continues to rotate in this direction, nut 16 travels toward the left, Fig. 2, until its post 16^a is engaged by post 10^a on the sleeve 10, rotating with the shaft 9, which will then rotate the nut 16 a partial turn from left to right.

The nut 16, by its engagement with pins 22, 22, on the cam carriage B will simultaneously rotate the cam carriage and its cams 24, 25, 26, from right to left, dotted line position Fig. 1, breaking their engagement, Fig. 3, with contacts 32^b, 31^b, 33^b, and, while still in engagement with contacts 40, 41, 42, Fig. 4, throwing said cams into engagement with the contacts 31^a, 32^a, 33^a.

When the timer 16 acts upon the cams 24, 25, 26, the cam 26 as stated, being shorter than the other two, is the first to break the switch circuit at the contact 33^b in the circuit line 34, line 48, plate 33, and line 37, to magnet 37^a. The result is that the magnet 37^a, being deenergized, the blade 37^e moves under action of the spring 37^e and breaks the circuit through line 35 from plate 31 to generator, and the cams 24, 25, after coasting a short time, come first into engagement with contacts 31^a, 32^a, and subsequently the cam 26, on account of its shortness, also comes into engagement with the contact 33^a.

When the cam 26 engages contact 33^a, Fig. 4, the circuit to the switch C is again established, and the current flows thereto by line 48, contact 42, cam 26, contact 33^a, plate 33, line 37, energizing magnet 37^a, causing blade 37^d to close the circuit through the line 35, and causing current to flow through line 34, plate 31, contact 31^a, cam 24, contact 40,

line 46, motor 47^a in reverse direction to line 47, contact 41, cam 25, contact 32^a, plate 32, line 35, through the switch C, to the generator.

When the direction of the operation of the driven member has been changed, the nut 16 will of course travel in the opposite direction until its post 16^b is engaged by the post 13^a on sleeve 13, when it and the cams will be again thrown, the current shifted to flow in the reverse direction as before and again reversing the direction of rotation of the driven member.

When starting the machine, the circuit breaking cams 24, 25, 26, will be positioned in contact with the contacts 40, 41, 42, and either contacts 31^a, 32^a, 33^a, or 31^b, 32^b, 33^b, according to the direction in which the machine was moving when it stopped.

Assume, for instance, that it stopped with the circuit breaking cams in position shown in Fig. 4: the switch C being open as per dotted line position Fig. 4. When the current is turned on the line 34 it will pass through lines 48, circuit breaking cam 26, line 37 to magnet energizing the same, closing switch C, causing the current to flow through line 34 and line 35 actuating the motor 47^a and starting the driven member.

The foregoing provides a simple and reliable construction for securing an equal number of rotations of the rotating member in each direction.

The distance of travel of the nut 16 in each direction being necessarily the same, inasmuch as it is engaged alternately by the posts 10^a and 13^a, it insures regular periodical reversal of the direction of rotation of the driven member.

Whenever it is desired to change the length of time that the driven member shall be operated in one direction, either to increase or decrease it, this may be done readily by simply loosening the screws 14^c in the collar 14 on the shaft 9, sliding the collar on the shaft to withdraw the teeth 14^b from the slots 14^a in the sleeve end, turning the sleeve 13 on the shaft 9 by means of the wheel 15 to increase or decrease the distance of the post 13^a from the post 10^a, and then again locking the sleeve 13 in adjusted position by means of collar 14 and the screws 14^c.

While I have herein described one embodiment of my invention it is obvious that the same may be modified in many details in construction without departing from the spirit of the invention and scope of the appended claims.

Claims:

1. Reversing mechanism comprising a plurality of operating circuits leading to a reversing motor, a switch circuit, including a switch controlling the operating circuits, means for connecting all the circuits with a

1. source of electricity, a shaft rotated from the motor, and means on the shaft for opening and closing at stated times the switch and operating circuits to effect reversal of motion of the driven member.
2. Reversing mechanism comprising a shaft, a combined timer and circuit breaker actuator thereon, a plurality of operating circuit breakers carried by the shaft, a switch circuit breaker also carried by the shaft; a motor, means for connecting the operating circuit breakers with the motor, means for connecting all the circuit breakers with a source of electricity, and a switch connected with the switch circuit breaker and controlling the operating circuit breakers and motor.
3. Reversing mechanism comprising a supporting member, a shaft thereon, a combined movable timer and circuit breaker actuator thereon, a plurality of constant contacts on the support, a plurality of oppositely disposed alternating contacts also thereon; a plurality of operating circuit breakers and a switch circuit breaker operated by the shaft, a motor, means for connecting the operating circuit breakers with the motor, and means for connecting all the circuit breakers with a source of electricity.
4. Reversing mechanism comprising a supporting member, a shaft thereon, a combined movable timer and circuit breaker actuator thereon, a plurality of constant contacts on said support, a plurality of oppositely disposed alternating contacts thereon, timer adjusting means adjacent the shaft; a plurality of operating circuit breakers and a switch circuit breaker on the shaft, a motor, means for connecting the operating circuit breakers with the motor, and means for connecting all the circuit breakers with a source of electricity.
5. Reversing mechanism comprising a supporting member, a shaft thereon, a combined movable timer and circuit breaker actuator thereon, a plurality of constant contacts on said support, a plurality of oppositely disposed alternating contacts also thereon, timer adjusting means adjustable relative to the shaft and controlling the extent of movement of the timer and times of reversal thereof; a plurality of operating circuit breakers and a switch circuit breaker on the shaft, a motor, means for connecting the operating circuits with the motor, and means for connecting all the circuit breakers with a source of electricity.
6. Reversing mechanism comprising a supporting member, a shaft thereon, a movable timer and circuit breaker actuator thereon, a plurality of constant contacts on said support, a plurality of oppositely disposed alternating contacts also thereon, timer adjusting means comprising a sleeve, adjustable on the shaft, and locking means therefor; a plurality of operating circuit breakers and a switch circuit breaker on the shaft, a motor, means for connecting the operating circuit breakers with the motor, and means for connecting all the circuit breakers with a source of electricity.
7. Reversing mechanism comprising a supporting member, a shaft thereon, a movable timer and circuit breaker actuator thereon, a plurality of constant contacts on said support, a plurality of oppositely disposed alternating contacts also thereon, timer adjusting means adjacent the shaft; a motor, means for connecting a plurality of alternating contacts with the switch and source of electricity, and means for connecting a plurality of constant contacts with the motor establishing operating circuits, a plurality of operating circuit breakers in the operating circuits, and a switch circuit breaker in the switch circuit, all the circuit breakers actuated by said timer.
8. Reversing mechanism comprising a supporting member, a shaft thereon, a movable timer and circuit breaker actuator thereon, a plurality of constant contacts on said support, a plurality of oppositely disposed alternating contacts also thereon; timer adjusting means adjacent the shaft, means for connecting a plurality of alternating contacts with the switch and the source of electricity, and means for connecting a plurality of constant contacts with the motor establishing operating circuits; a circuit breaker and current distributing carriage movably mounted and actuated by said timer, a plurality of operating circuit breakers in said operating circuits, and a switch circuit breaker in the switch circuit, and on said carriage.
9. Reversing mechanism comprising a supporting member, a shaft thereon, a movable timer and circuit breaker actuator thereon, a plurality of constant contacts on said support, a plurality of oppositely disposed alternating contacts also thereon; timer adjusting means adjacent the shaft, means for connecting a plurality of constant contacts with the motor and means for connecting a plurality of alternating contacts with a source of electricity and the switch establishing operating circuits; a circuit breaker and current distributing carriage rotatably mounted, a plurality of operating circuit breaking cams on said carriage and in the operating circuits, a switch circuit breaking cam on said carriage and in the switch circuit.
10. Reversing mechanism comprising a supporting member, a shaft thereon, a movable timer and circuit breaker actuator thereon, a plurality of constant contacts on said support, a plurality of oppositely disposed alternating contacts also thereon; timer adjusting means adjacent the shaft, means for

connecting a plurality of constant contacts with the motor and means for connecting a plurality of alternating contacts with the switch establishing operating circuits; a circuit breaking carriage rotatably mounted on said shaft and within the field of said contacts, a plurality of operating circuit breaking cams in said operating circuits, and a switch circuit breaking cam in said switch circuit, all on the carriage.

11. Reversing mechanism comprising a supporting member, a shaft thereon, a movable timer and circuit breaker actuator thereon, a plurality of constant contacts on said 15 support, a plurality of oppositely disposed alternating contacts also thereon; timer adjusting means adjacent the shaft, means on the shaft for adjusting the timer controller relative thereto to regulate the time of reversal of the timer; means for connecting a plurality of alternating contacts with the switch and means for connecting a plurality of constant contacts with the motor establishing operating circuits; a circuit breaking 20 carriage rotatably mounted on said shaft within the field of said contacts, a plurality of operating circuit breaking cams in said operating circuits and a switch circuit break-

ing cam in the switch circuit, all on said carriage; said operating and switch circuit breaking cams normally in contact with said constant contacts and one set of alternating contacts, and adjusting means on the carriage for said circuit breakers.

12. Reversing mechanism comprising a 30 casing, a cam carriage mounted to rock therein, carrying operative circuit closing cams and a switch circuit closing cam, each in an electrical circuit, a plurality of alternating contacts, and a traveling timer for actuating 40 the circuit closing cams to alternately engage the alternating contacts.

13. Reversing mechanism comprising a 35 casing, electrical operating and switch circuits therein, constant contacts therein, 45 alternate contacts therein, operating circuit breakers in the operating circuits, a switch circuit breaker in the switch circuit controlling the opening and closing of the operating circuits, and adjusting means for determining the time for opening and closing of said circuits.

In testimony whereof, I have signed my name to this specification.

FRITZ W. A. HENRICI.
